(57) **CLAIM**

The ornamental design for a display screen with graphical user interface for a laser-phacoemulsification system, as shown and described.

DESCRIPTION

FIG. 1 is a front view of a display screen with graphical user interface for a laser-phacoemulsification system in accordance with a first embodiment of the new design; and, FIG. 2 is a front view of a display screen with graphical user interface for a laser-phacoemulsification system in accordance with a second embodiment of the new design.

The broken lines representing the graphical user interface are included for the purpose of illustrating unclaimed portions of the article. The outer broken lines that illustrate a frame represent a display screen for a laser-phacoemulsification system. The broken lines form no part of the claimed design.

1 Claim, 2 Drawing Sheets
